UNITED STATES PATENT OFFICE.

JAMES HUNDLEY, OF MIDDLEPORT, OHIO.

CHARGING DEVICE FOR FURNACES.

1,280,037.

Specification of Letters Patent. Patented Sept. 24, 1918.

Application filed October 21, 1916. Serial No. 126,850.

To all whom it may concern:

Be it known that I, JAMES HUNDLEY, a citizen of the United States, and a resident of the city of Middleport, county of Meigs, 5 and State of Ohio, have invented certain new and useful Improvements in Charging Devices for Furnaces, of which the following is a specification:

My invention relates to improvements in 10 charging devices for heating furnaces, and more particularly to that type of furnace designed for heating and reducing iron or steel or similar refractory substances, and has more definite relation to that particular type 15 of furnace as shown and designated in U. S. Patent #634,499, said patent being granted on October 10, 1899, to the inventor hereof, and this invention is an improvement on and amplification of said patent and covers developments thereof which have been found 20 essential and vital as the result of the commercial operation of said device.

A particular object of the present invention is to secure the pillows or bricks, as designated in said patent, against turning or swiveling on the charging pipes, and to prevent them falling off or being lifted off when loading, unloading or heating the iron piles which rest thereon. A further particular 30 object is to prevent the charging pipes or tubes from sagging within the furnace under the influence of the impinging heat or flame, and the weight or load of the piles imposed thereon. A further object is to protect said 35 pipe supporting means from injury or destruction, due to excessive heating within the furnace.

The general embodiment of my invention is illustrated in the accompanying drawings, 40 although it should be distinctly understood that I do not desire to restrict myself to the precise embodiment herein stipulated, but claim such modifications as come legitimately within the spirit of this invention.

With more particular reference to the appended drawings, and to the drawings of U. S. Patent #634,499, in which similar numerals refer to similar parts throughout, and in which the numerals of the former patent 50 have, in so far as they relate to the present invention, been employed to designate corresponding parts of the present invention;—

Figure 1 illustrates a vertical cross section of a conventional furnace with the charging 55 device installed. Fig. 2 shows a cross sectional elevation of a detail of the pipe sup-

porting means, with a fragment of the pipe in place, said elevation being taken on line 2—2 of Fig. 3. Fig. 3 is a sectional elevation of the same detail taken medially of Fig. 2. Fig. 4 is a cross section of a preferred form of pipe, having a pillow or brick in place. Fig. 5 is an alternative form of pipe, having side lugs or ribs instead of indentures. Fig. 6 is a still further alternative 65 arrangement of the pipe in which the ribs are enlarged and chambered to provide for cooling. Fig. 7 is a further arrangement of pipe, having flattened sides instead of ribs or indentures, and Fig. 8 shows a plain 70 cross section of pipe with brick surrounding a major portion thereof to secure brick against being lifted off.

In the drawings, the numeral 5 designates the walls of the furnace in general, having a 75 charging door or opening 4, and any suitable bed or floor 6 of suitable refractory material, the opening 4 being closable by the door 7 controlled by lever 8 through link 9. 10 designates the piles or blocks of iron to be 80 heated which rest on the pillows or bricks 19 imposed on or attached to the hollow pipes or tubes 14, which pass through the opening 4 at the front of the furnace and any suitable openings 15 at the rear of the 85 furnace. 13 designates the heating chamber which may be heated by any suitable furnace, not shown. The pipes 14 are cooled by a flow of water or other element therethrough, 90 said water being supplied through the hose 16 attached to upright pipe 18 and discharged through upright 18' and hose 16'. Pipes 14 are supported on suitable rollers or other supports 21 maintained in standards 23 without the furnace, and within the 95 furnace are supported on rollers 20 maintained on standards 22. These standards are preferably embedded within the floor 6 to protect them from the furnace action. Rollers 20 revolve on tubular shafts 24 supported in standards 22, said shafts being supplied with a flow of water through pipes 31, said water discharging through pipes 32, 100 shafts 24 being estopped medially of roller 20 by any suitable wall or estoppage 25. 105 Roller or sheave 20 is hollow or chambered, as at 30—30', having a medial wall 28, said wall having suitable openings or passages 29 therethrough. Shafts 24 are provided with openings 26 on one side of the estoppages 110 and 27 on the opposite side of said estoppages.

With more direct reference to construc-

tion of tubes 14 and pillows 19, the numeral 33 indicates longitudinal indentures or recesses, preferably diametrically opposed within the walls of said pipe, the pillow 5 having a tongue or projection 34 to register with said indenture, the pipe being flattened, as shown at 35, at some suitable position to allow the placing of the bricks thereon. 36 indicates a rib or projection on said pipe 10 to register with corresponding indentures in the pillow which may be utilized as an alternative to the previous construction, said rib being removed, as at 37, to allow the placing of the bricks. In 38 this rib is 15 shown enlarged and chambered or hollowed, as at 39, to allow the water to cool said ribs, the ribs being discontinued at any suitable location, as at 40, to allow the placing of the pillows. In Fig. 7 the pipes are shown with 20 flattened sides 41 to prevent bricks from oscillating or swiveling, although this construction does not prevent their being lifted off with the piles. In Fig. 8 the pipes are used with neither indentures nor ribs, the 25 bricks 19 surrounding a major portion of the pipes, which prevents their being lifted off, but does not prevent their swiveling, the pipes being flattened, as at 42, to allow the placing of the bricks.

30 In operation the iron or steel piles are placed on the bricks resting on the pipes without the furnace, and pipes are then moved forward over their supporting rollers to carry piles through the furnace door into 35 the heating chamber, the flexible hose allowing such longitudinal movement. During the heating the pipes are cooled by the passage of water through the pipes and the internal supporting rollers are cooled by forcing water through pipes 31 through the hollow shafts 24 from thence through openings 40 26 into chamber 30 through openings 29 into

chamber 30' through openings 27 and out through pipe 32, thus maintaining a uniform temperature of suitable degree within the shafts and rollers during the process of heating. Any required number of pillows or 45 bricks may be placed on the pipes, of which any suitable number may be employed, the bricks being placed upon the pipes at the special point provided, and moved longitudinally thereon to the required point of loading. The special provisions designated prevent the pillows from swiveling or falling off, maintain the loads in an upright position and prevent the pillows from being lifted off the pipes with the piles after heating. 50

Having thus described my invention, what I claim as new and desire to protect by these 60 Letters Patent, is:

In a heating chamber of a heating furnace intended for heating piles, the combination of hollow bars for supporting said piles within said chamber, bricks or pillows supported on said hollow bars between said bars and said piles, longitudinal ribs integrally formed upon the exterior circumference of said bars, indentures formed within said bricks or piles to co-act with said longitudinal ribs to prevent rotation of said bricks upon said bars, said longitudinal ribs being eliminated for a portion of the length of said bars to facilitate the placing of said bricks upon said bars, as and for the purpose 65 70 75 described.

In testimony whereof I have signed my name to this specification in the presence of two subscribing witnesses.

JAMES HUNDLEY.

Witnesses:

CLYDE HACKETT,
CHAS. HUGHES.
